UNITED STATES PATENT OFFICE.

THOMAS F. N. FINCH, OF WORCESTER, ENGLAND.

DESIGN FOR BUTTONS.

Specification forming part of Design No. **11,137**, dated April 1, 1879; application filed March 6, 1879.
[Term of patent 3½ years.]

To all whom it may concern:

Be it known that I, THOMAS F. N. FINCH, of Worcester, in the county of Worcester, England, have invented a new and original Design for Buttons, of which the following is a specification:

My design consists in making a button in the form of and resembling a knot.

The accompanying drawings represent this design, Figure 1 being a top or face view of the button embodying it, and Fig. 2 being a side view thereof.

A designates the body of the button, and B the shank thereof, of the usual or any suitable shape. The body A may be made of solid leather, and is formed like and so as to resemble a knot in a thong or strip of leather or other material, so that when fastened to any object it will simulate a knot on the same. It may have a surrounding rim, b. Colors should be employed to enhance the resemblance to the knotted material of which the button is an imitation.

What I claim as my invention, and desire

to secure by Letters Patent, is—

A design for a button, consisting in making the same in the form of and resembling a knot, substantially as specified.

THOMAS F. N. FINCH.
